UNITED STATES PATENT OFFICE.

OTHO M. OTTE, OF JAMESTOWN, NEW YORK.

MEANS FOR ANCHORAGE FOR ENAMELED-METAL-WARE PARTS.

1,286,746.

Specification of Letters Patent.

Patented Dec. 3, 1918.

Application filed July 22, 1918. Serial No. 246,245.

To all whom it may concern:

Be it known that I, OTHO M. OTTE, a citizen of the United States, residing at the city of Jamestown, in the county of Chautauqua 5 and State of New York, have invented certain new and useful Improvements in Means of Anchorage for Enameled-Metal-Ware Parts, of which the following, taken in connection with the accompanying drawings, 10 is a specification.

The invention relates to means for fastening or attaching enamel metal ware parts to a support; and the improvement consists in providing concealed stooled, bridged or 15 strutted clips or brackets having a spaced attachment to a metal sheet or part, the braces or legs having contacting surfaces on said sheet or part of small size preferably about equal in area to the point of the 20 electrode in the spot welding machine, thereby reducing to a minimum the mass of metal abutting and allowing the cooling of the enameled metal steel to be practically uniform at all points, thereby removing 25 stresses or strains caused by unequal heating or cooling during the processes of enameling, the clip or bracket connection being so shaped that an additional cooling area of metal is placed immediately adjacent to the 30 attaching braces or legs, thus overcoming said unequal heating or cooling where the thickness of metal has been increased by the attachment of said clips or brackets, and thereby providing said attaching clip or 35 bracket in a definite spaced relation to the main sheet of metal prior to its enameling so that it may be subjected to the requirements in the process of vitreous or high heat enamel on steel preventing buckling, twisting 40 and raising even in thin metal sheets when subjected to approximately 1600 degrees Fahrenheit as required for said vitreous enamel on steel, the gage of metal in both sheet and bracket being preferably the 45 same, said clips or brackets preferably having openings between the braces or legs to better equalize said stresses and strains by freely admitting the air between the bracket and sheet at the points of attachment.

50 This method or means of concealed attachment is used for enameled plates on

stoves, enameled refrigerators, cabinets and tops and shelves of enameled hospital fixtures of all sort; also for enameled sliding tops on metal kitchen cabinets, tables and 55 similar articles of furniture to which said clips or brackets may be attached by means of screw bolts, pins or rivets; and the invention consists in the novel features and combinations hereinafter set forth and claimed. 60

In the drawings, Figure 1 is a perspective view of the preferred form of the attaching clip or bracket for enameled plates or metal ware showing the stooled or spaced attachment to a portion of the plate and the slotted 65 openings for attachment of the bracket to a support as desired; and Fig. 2 is a perspective view of the bottom of the preferred form of said bracket; and Fig. 3 is a similar view of the bottom of said bracket showing 70 three attaching stools having level faces and different shaped cooling openings therebetween; and Fig. 4 is a sidewise elevation of said preferred form of bracket showing the spaced relation between the enameled plate 75 and the bracket by means of the strutted or stooled arrangement, the doubly enameled plate being shown in section. Fig. 5 is a sectional view of the enameled plate for a sliding top of a table or similar article showing the attaching brackets in section at lines 80 5—5 in Figs. 1 and 3 for different styles of sliding ways and channeled supporting strips which stiffen and hold the enameled plate in line. Fig. 6 is a sectional view of the enameled plate showing a modification 85 of the preferred form of bracket; which modification is further illustrated in Figs. 7 and 8 showing a rectangular bridged or stooled bracket by means of corner legs 90 welded to the enameled top or plate and having attached slots therein. Fig. 9 is a further modification of the attaching clip or bracket showing its attachment to a channeled strip and reducing the area of the contacting surfaces or holding points on said enameled top; and Fig. 10 is a sectional view at line 10—10 in Fig. 9 of said modification showing the welding point and the point contact of the side braces. Fig. 11 is a 100 further modification of the design of bracket shown in Figs. 9 and 10 in which two out-

wardly turned attaching or welding lugs are provided. Figs. 12, 13 and 14 show perspective views and an elevation of a modification of the preferred form of clip or bracket shown in Figs. 1-5 in order to provide a clip or bracket of enlarged size, the sheet contacting surface being elongated and the cooling opening between said stooled contacting surfaces enlarged in the elongated clip or bracket. Fig. 15 is an elevation of said modified form of clip or bracket shown in Figs. 9 and 10 as attached in spaced relation to a table top or other metal plate preparatory to the concealed attachment of the same to a support.

Like characters of reference refer to corresponding parts in the several views.

The numeral 20 designates the metal plate usually of sheet steel and oftentimes of light gage to which is attached in spaced relation a struttied or stooled clip or bracket as hereinafter described.

In the preferred form of bracket 21 or 22, the sheet metal plate 20 has the opposite surface from that to which the bracket 20 is attached provided with a heavy vitreous or high heat enamel coating 23 while the surface to which the bracket 21 is attached is usually uncoated as shown in Figs. 1 and 5, though a light coat 24 is shown in Fig. 4 on the attaching side for the clip of bracket 21. The bracket 21 or 22 is provided with a plurality of spaced legs 25 preferably having a cooling opening or openings 26 therebetween to admit the air to the space between the bracket 21 and the metal plate 20 during the process of enameling, the bracket 21 being attached to the plate 20 before enameling.

The legs 25 of the bracket 21 are preferably provided by a multiple punch in a die press which shapes said legs 25 exactly alike with each of said legs having a flat level contacting surface or face for the plate 20 about the size of the spot welding tool so that said tool may be inserted in the cup 27 formed by the punch in shaping the leg 25, a multiple point spot welding tool being preferably used having a series welding contact.

The sides 30 of the bracket 21 are preferably made in the triangular shape so as to brace the bracket and at the same time provide a braced connecting side having the slots 28 and 29 preferably in right angle relation therein for attachment by means of screw bolts or rivets to a channel strip 36 or sliding way 43 or other support. The triangular sides 30 of the preferred form of bracket brace the bracket so strongly that the same cannot bend or get out of line. In order to make this preferred form of bracket from the flat sheet metal in one operation, a die is provided which punches the legs 25 at a slight angle of inclination as shown

at 31 in Fig. 4. This arrangement permits the easy withdrawal of the punch from the cups 27 and the cupping bracket 21 whether two or three or more cups 27 for legs 25 are provided. Part of said cups are shown straight, instead of inclined as shown in Fig. 4, since the straight legs could be easily and quickly made by a separate die from the one forming the remainder of the bracket. The inclined legs as shown at 31 are only used for a die which punches the legs 25 and shapes the bracket at the single operation.

A modification of the preferred form of bracket 21 is shown in a multiple leg or bridged clip or bracket 32 in which the legs extend down from both ends of a rectangular shaped plate or clip which is thereby bridged in its attachment to the sheet metal plate 20, the points of welding attachment 33 being made with a small area so as to provide as small an extra heated surface as possible and has large additional cooling area of metal in the bracket 32 immediately adjacent to the welding legs 33, thus overcoming the unequal cooling of the sheet steel where the thickness has been doubled by the attachment of said legs.

This overcoming of the unequal cooling is a fundamental requirement since, as stated, the high heat required in applying vitreous or high heat enamel on steel, being approximately 1600 degrees Fahrenheit, and the light gages of steel used make the liability to buckle, raise or twist much greater. Accordingly small pointed copper electrodes are used in the spot welding machines and the foot of the legs 25 or 33 are about equal in area to said electrode points.

Another modification of the preferred form of bracket is shown at 34 in Figs. 9, 10, 11 and 15 in which the substantially triangular design of the preferred form of bracket is shown. The modification cuts away the base plate with the exception of an attaching lug 35 which is angularly shaped so as to weld to the sheet metal plate 20 and has the vertical and horizontal slots 28 and 29 therein for attachment to a channel strip 36 or similar support or attaching means. The triangular sides or wings 37 are given a downward inclination so as to brace squarely against the plate 20 when attached thereto and gives a strong holding attachment to certain kinds of supports especially those wherein the points of the wings 37 are braced against plate 20 and a holding support to which the bracket 34 is attached. For certain purposes two end lugs 38 may be provided in place of the single central lug 35 thereby giving a stronger attachment to the metal plate 20.

The preferred form of holding bracket 21 may be doubled in its holding capacity as shown in Figs. 12, 13 and 14 in which a

- double set of slots 28 and 29 are provided and elongated cups 39 and legs 41 with the large cooling opening 40 therebetween. The slots 28 and 29 permit the adjusted attachment of the channel strip 36 or other holding means to which the bracket or brackets are attached so that said strip 36 may be attached in contact with the enamel plate 20 or a spaced distance therefrom.
- 10 The space 42 between the metal sheet 20 and the clips or brackets 21, 32 and 34 is provided in order, first, to prevent said unequal cooling; and second, so that a coat of enamel may be applied on the side of the metal sheet 20 adjacent said brackets; and third, so that said enamel may be blown out from beneath said brackets and sponged off after dipping when it is desired not to coat the bracketed side of the metal plate 20. It is apparent that this construction provides a simple and strong concealed attachment for the vitreous enameled parts without danger of chipping or cracking said enamel during said attachment, as is the case with screws, bolts and similar means. Said concealed attachment also leaves the enameled surface smooth and clean without unsightly screw heads or attaching plates.
- I claim as new:—
- 30 1. An anchorage for enameled parts comprising an attaching clip or bracket welded in spaced relation to the metal sheet before enameling to prevent distortion of said metal sheet under the high heat of the enameling process.
2. An anchorage for enameled parts comprising attaching clips or brackets attached to the metal sheet to be enameled in spaced relation thereto before enameling to prevent distortion of said sheet under the high heat of the enameling process.
- 40 3. An anchorage for enameled parts comprising an attaching clip, spaced legs on said clip, a metal sheet to be enameled, said spaced legs welded to said metal sheet before enameling to hold said clip and metal sheet in spaced relation and permit air cooling and thereby prevent distortion of the said metal sheet under the high heat necessary for enameling.
- 50 4. An anchorage for enameled parts comprising a metal sheet to be enameled, spaced attaching clips or brackets for said metal sheet, spaced legs on said clips welded to said metal sheets before enameling to hold said clips and metal sheet in spaced relation to prevent distortion, said clips having openings therein between said spaced legs to admit air circulation around said legs close to the welding points to overcome the unequal cooling of the doubled sheet metal at the point of attachment.
- 60 5. A concealed anchorage for enameled parts comprising a metal sheet to be enameled, spaced sheet metal attaching clips or brackets for said metal sheet, spaced legs on said sheet metal clips or brackets formed cup shaped by a punch press die, said clips attached to said metal sheet on its unexposed side by spot welding through the bottoms of said cup-shaped legs.
- 65 6. A concealed anchorage for enameled parts comprising a metal sheet to be enameled, and sheet metal attaching clips or brackets attached to said metal sheet in spaced bridging relation on its concealed side by means of spaced legs welded to said metal sheet through their contacting feet before enameling, said space between the sheet and clips or brackets being provided to allow blowing of the coating formed by the enameling solution from beneath said attaching clips or brackets and the wiping of said solution from the remaining concealed side of said metal sheet, and also the subjecting of said clipped or bracketed metal sheet to sufficiently high heat to change said solution to hard enamel.
- 70 7. A concealed anchorage for enameled parts comprising the metal part to be enameled, an angular attaching clip or bracket having triangular shaped bracing ends struck from sheet metal, cup-shaped legs struck up in said attaching clip or bracket by a suitable punch press die, said legs attached to said metal part to be enameled by spot welding through the flat bottoms of said metal cups, said clips or brackets having openings therein for attaching bolts.
- 75 8. A concealed anchorage for vitreous enameled parts comprising the metal plate to be enameled, cupping angular clips or brackets having a flat base and straight side angular to said base, said straight side having angular slots therein for attaching bolts, a plurality of cup-shaped flat bottomed legs struck up in spaced relation in said flat base, said clips or brackets attached to said metal plate by spot welding said flat bottomed cup-shaped legs to the concealed side of said metal plate, and a coating of vitreous enamel on the exposed side of said metal plate after the attachment of said clips or brackets.
- 80 9. An anchorage for enameled metal parts including an attaching element, and means whereby to weld said element to the metal parts before enameling and with air space between the element and parts to prevent distortion of the latter under the high heat of the enameling process.
- 85 10. An anchorage for enameled metal parts including an attaching element and means whereby to weld said element to the metal parts before enameling and with space in free communication with the surrounding atmosphere between the element and parts.

to prevent distortion of the latter under the high heat of the enameling process.

11. An anchorage for enameled metal parts including an attaching element, and means whereby to weld said element to the metal parts before enameling and with the points of weld completely encircled by the surrounding atmosphere to prevent distortion of the parts under the high heat of the enameling process.

10
In testimony whereof I have affixed my signature in the presence of two witnesses.
